CARPET SWEEPER

Charles M. Youart, Shelbyville, Ind., assignor to
 Porter Steel Specialties, Shelbyville, Ind., a
 partnership consisting of Enos Porter, Hester
 Porter Fuller, Geo. M. Parker, and Charles M.
 Youart

Application August 14, 1937, Serial No. 159,045

5 Claims. (Cl. 15—41)

The object of my invention is to provide improved means by which the dust pans of carpet sweepers may be manipulated to dump the contents.

5 The accompanying drawing illustrates my invention:

Fig. 1 is an end elevation, in partial vertical section, of a sweeper in which my improved structure is incorporated;

10 Fig. 2 is a vertical section in a plane parallel with that of Fig. 1; and

Fig. 3 is a fragmentary vertical section in a plane at right angles to that of Fig. 2.

15 In the drawing 10 indicates the usual main casing of the sweeper to each end wall 11 of which is secured a plate 12 carrying an outwardly projecting fixed stud 13. Pivoted upon studs 13 are the depending arms of the usual handle-bail 14. The main casing is supported 20 by the usual wheels 15 which drive the brush 16.

Pivotedly supported within the casing, at 17, 17, are the dust pans 17', 17' which are normally held in the closed positions, shown in Fig. 2, by the divergent arms of springs 18 (one at each 25 end). Thus far the structure is common and well known.

Each spring 18, at its middle, is formed into an eye 18' into which is projected a pin 19 each carried by a depending arm 20 of a yoke 21 the 30 middle bar of which parallels the middle bar of the handle-bail 14. The pins 19 project through short vertical slots 22 formed through the end walls 11 of the casing in the region of eyes 18'.

Movement of the yoke 21 upwardly, to move pins 19 upwardly in slots 22, will move the springs 18 upwardly to cause the dust pans to swing on their pivots 17 to dump the contents of the pans.

If the slots 22 are left uncovered dust will be thrown by the brush into the slots and will there 40 accumulate so as to block proper movement of pins 19 in the slots. As the slots 22 must be located very closely beneath the top of the casing, I provide a rotary cover plate 25 for each slot pivoted at 26 on the inner face of the end wall 45 and provided with spaced fingers 25' and 25'', finger 25' overlying the slot 22 above and engaging pin 19 and finger 25'' underlying and engaging pin 19. Finger 25'' is provided with a bent-back finger 25''' which overlies the adjacent spring 18, finger 25''' thus serving to retain the spring against accidental displacement from its engagement with pin 19.

The yoke 21 might pivot freely in the eyes 18' of springs 18 with the middle bar of the yoke 50 normally lying upon the top of casing 10.

I prefer, however, to provide yoke 21 with portions 30 which slidably straddle or embrace the adjacent depending arms of the handle-bail 14, so that the yoke will partake of the swinging movements of the handle-bail and thus be at all times in convenient position for manipulation upwardly to cause dumping of the dust pans.

5 The springs 18 and the dust pans, as is usual in this type of construction, are so proportioned that these parts normally tend to assume the 10 positions shown in Fig. 2, so that, after manipulation of the yoke 21 upwardly and following release of said yoke, the pans, springs and yoke will automatically return to their positions 15 shown in Fig. 2.

A single connection between the dust pans and an external operating element 20 will produce an operative structure, but I prefer the balanced construction such as shown and described.

20 I claim as my invention:

1. In a sweeper, the combination of the main casing having a handle-bail pivoted thereon on a fixed axis through which downward pressure may be applied to the casing, dust pans pivotally 25 mounted in the casing, and a yoke movable independently of the bail and having depending arms connected with said dust pans, a portion of said yoke closely paralleling a portion of the handle-bail whereby said portions may be simultaneously grasped for operation of the yoke.

2. In a sweeper, the combination of the main casing having a handle-bail pivoted thereon on a fixed axis through which downward pressure may be applied to the casing, dust pans pivotally 35 mounted in the casing, an inverted V-spring connecting said pans at each end, and a vertically movable yoke, the depending arms of which carry substantially horizontal pins having portions lying within the casing and pivotally associated with said springs, and a slidable connection between said handle-bail and yoke whereby the yoke will partake of the swinging movements of the handle-bail.

3. In a sweeper, the combination of the main 45 casing having a handle-bail pivoted thereon on a fixed axis through which downward pressure may be applied to the casing, vertical slots formed through the end walls of the casing in the regions of the pivots of said bail, dust pans pivotally mounted in the casing, an inverted V-spring connecting said pans at each end, a yoke 50 vertically movable independently of the handle-bail and having depending arms which straddle the casing, and pins projecting inwardly through 55

- said slots and into engagement with said springs, a plate pivoted on the inner face of each end wall of the casing adjacent the slot, said plate having a portion overlying the adjacent slot
- 5 when the pans are closed, said plate engaging the adjacent yoke pin to be swung thereby upon lateral movement of the pin in the slot.
4. In a sweeper, the combination of the main casing having a handle bail pivoted thereon on
- 10 a fixed axis through which downward pressure may be exerted on the casing and vertical slots formed through the end walls in the regions of the pivots of said bail, dust pans pivotally mounted in the casing, a vertically movable yoke
- 15 the depending arms of which straddle the casing and have pins projecting inwardly through said slots, connections between said pins and pans whereby lateral movements of said pins in said slots are accompanied by movement of the pans

on their pivots, and a slidale connection between said yoke and handle bail whereby the yoke will partake of the swinging movements of the handle bail.

5. In a sweeper, the combination of the main casing having vertical slots formed through its end walls, dust pans pivoted within the casing, a yoke the depending arms of which straddle the casing and have pins projecting through said slots into the interior of the casing, connections 10 between said pins and the dust pans whereby lateral movement of the pins in the slots will be accompanied by swinging movement of the pans, and a plate pivoted adjacent the slot, said plate having a portion normally covering the slot adjacent the pin and the plate also engaging the pin so as to be swung thereby upon lateral movement of the pins in their slots.

CHARLES M. YOUART.
